United States Patent Office

Des. 222,362
Patented Oct. 19, 1971

222,362

ELECTRIC POWER DISTRIBUTION APPARATUS

James R. Williams, Berkeley, Calif., assignor to
Williams & Lane, Inc.

Filed Dec. 24, 1969, Ser. No. 20,647

Term of patent 14 years

Int. Cl. D13—01, 02
U.S. Cl. D26—15

F i g. 2

F i g. 3

Fig. 4

Fig. 5

Fig. 6

FIG. 1 is a perspective view of an electric power distribution apparatus showing the design;

FIG. 2 is a rear elevation of the apparatus;

FIG. 3 is a bottom plan view of the apparatus;

FIG. 4 is a top plan view of the apparatus as seen from the rear side and with one of the covers lifted as depicted in FIGS. 1 and 2;

FIG. 5 is a front elevation of the apparatus; and

FIG. 6 is an end elevation of the apparatus.

The opposite end of the apparatus is the same as shown in FIG. 6.

I claim:

The ornamental design for an electric power distribution apparatus, as shown and described.
